REUBEN B. HILLS, OF NORTHAMPTON, MASSACHUSETTS.

COMBINATION STOP AND WASTE AND SAFETY VALVE.

1,198,128.

Specification of Letters Patent. Patented Sept. 12, 1916.

Application filed November 12, 1915. Serial No. 61,155.

To all whom it may concern:

Be it known that I, REUBEN B. HILLS, a citizen of the United States of America, residing at Northampton, in the county of 5 Hampshire and State of Massachusetts, have invented a new and useful Combination Stop and Waste and Safety Valve, of which the following is a specification.

My invention relates to improvements in 10 valves designed to control the water supply to houses and other buildings, and which are usually installed back of the meters generally provided in such houses or buildings, and said invention resides in a casing having 15 therein a loose check valve and a normally-closed waste valve, and equipped with certain peculiar means for positively closing the first and opening the second of said last-mentioned two valves, all as herein- 20 after set forth.

The primary object of my invention is to produce a manually-controlled stop and waste valve and an automatically-operated safety valve, all in a single for unitary 25 structure, to the end that the supply of water which passes through this device can be shut off and let on readily, and the waste water when the supply is shut off can escape 30 freely and so clear the pipes back of said device, on the one hand, while any excessive pressure, as from the overheated contents of a hot-water boiler is relieved and taken care of so that the aforesaid pipes are not injured or the meter turned backward, on the 35 other hand. As is well known, too great a pressure in the interior supply pipes is liable either to burst the pipes or cause the mechanism of the meter to be reversed, or it may do both, but with my valve neither 40 of these results can occur. With a single device, therefore, I attain a two-fold object, as explained above.

A further object is to produce a combination valve of this nature which has a 45 straight water-way through the same, is strong and durable yet simple in construction and operation, compact, comparatively inexpensive to manufacture, and withal highly practicable and efficient.

50 Other objects and advantages will appear in the course of the following description.

A practical and preferred embodiment of the invention, whereby I attain the objects and secure the advantages of the same, is 55 illustrated in the accompanying drawings, and I will proceed to describe the invention

with reference to said drawings, although it is to be understood that the form, construction, arrangement, etc., of the parts in various aspects are not material and may be 60 modified without departure from the spirit of the invention.

In the drawings, in which like numerals 65 designate like parts throughout the several views, Figure 1 is a central vertical section through a combination valve which embodies a practical and preferred form of my invention as aforesaid, the check-valve member being open and the waste-valve member being closed; Fig. 2, a generally similar 70 view, except that fewer parts are in section, wherein the positions of said valve members are reversed, that is, the check valve is closed and the waste valve open; Fig. 3, a top plan view of the valve casing, and, Fig. 75 4, what may be termed a front elevation of the valve-operating sleeve.

There being two valves proper in this device, they will sometimes be referred to herein as valves simply, without their respective descriptive adjectives, while the device as a whole will be referred to as a combination valve.

The combination valve of the drawings is described in detail as follows, it being observed first that the same comprises a casing 1, two valves 2 and 3, a rotatable spindle 4, an operating sleeve 5 for said valves, such sleeve being reciprocated by means of said spindle, and certain auxiliary and subsidiary 90 parts and members.

The casing 1 has therein a central chamber 6, a horizontal supply inlet 7 to such chamber, which inlet communicates with said chamber through a valve-seat 8, a supply outlet 9, from said chamber, which outlet is in line with said inlet, a waste outlet 10 from the bottom of said chamber and with which the latter communicates through a valve-seat 11. A hollow cap 12 having an 100 opening 13 in the bottom thereof is tapered into the outlet 10. The waste and excess pressure escape and find relief through the valve-seat 11 and the opening 13.

The top of the chamber 6 is closed by a 105 cap 14, which latter is provided as usual with a stuffing-box 15 and plug 16 for the spindle 4. Within the stuffing-box 15 are washers or rings 17 and 18 and packing material 19. The ring 17 fits tightly on the 110 spindle 4, and this ring with a shoulder 20 on said spindle under the stuffing-box 15

hold said spindle against endwise movement without interfering with the rotation thereof. A packing-ring 36 is inserted between the upper edge of the casing 1 or of 5 the walls of the chamber 6 and the adjacent part of the cap 14.

The spindle 4 below the shoulder 20 has a coarse thread 21 to engage a similar thread, indicated at 22, within the sleeve 5, so that 10 when said spindle is rotated in one direction said sleeve is elevated and when rotated in the other direction the sleeve is depressed or actuated downward. At the top of the spindle 4 is a handle 23.

15 In the side walls of the chamber 6 are two vertical oppositely-disposed grooves 24, and the sleeve 5 has lateral oppositely-disposed vertical ribs 25-25 to run in said grooves. By means of the ribs 25 and the grooved 20 portions of the casing 1 in which said ribs travel, the sleeve 5 is held to its vertical course and absolutely prevented from rotating and from being forced out of such course. On the front side of the sleeve 5 is a lug 26, and at the base of said sleeve is a 25 foot-piece 27. The continued axis of the spindle 4 with the sleeve 5 passes through the axial center of the valve-seat 11, in the present arrangement of parts.

30 The valve 2, which is of the loose flapper type, is the check valve of the device, while the valve 3, which is of the puppet type, is the waste and relief valve of the device.

The check valve 2 is pivotally mounted at 35 the top on a horizontal bolt 28 set in the casing 1. This valve consists in part of a packing or face member 29 secured in place by a threaded post 30 and nut 31, and the arrangement is such that said member contacts with the inner surface of the edge of 40 the inlet opening for the chamber 6, or from the inside of said chamber engages and closes the valve-seat 8, and so shuts off the flow of water to said chamber, when said 45 valve is swung down into a vertical position and forced against said valve-seat. The lug 26 rides down the valve 2 on the inside, when the sleeve 5 is caused to descend, and forces said valve or its packing 29 tightly 50 against the valve-seat 8.

The waste valve 3 has a packing 32 to engage the valve-seat 11 from below and close the opening through such seat. A stem 33 depends from the valve 3 into the cap 12, and a spiral spring 34 is interposed between 55 said valve and the bottom of said cap, encircling said stem, normally to retain the valve in closed position. Rising from the valve 3 into the opening through the valve-seat 11 is a stem projection 35 which is in the path of the foot-piece 27 when the sleeve 5 descends. The projection 35 is made smaller in cross section than the opening 60 through the valve-seat 11, or angular as 65 shown, in order not to obstruct unduly such

opening when the valve 3 is open. The valve 3 is forced open, against the resiliency of the spring 34, by the foot-piece of the sleeve 5, whenever the latter is forced down by the spindle 4.

70 While the sleeve 5 is in its high position, the water flows freely through the casing 1, entering the casing at 7, passing through the valve-seat 8 into the chamber 6, on the way forcing open the valve 2 and retaining 75 said valve in open position, passing from said chamber to the outlet 9, and escaping from the casing at said outlet. The valve 2 is held up, by the force of the water flowing 80 through the casing 1, against the base of the sleeve 5 at the front edge, in the position shown in the first view. Meanwhile the valve 3 is retained in closed position by the spring 34.

Assuming, now, that it is desired to shut 85 off the water, the spindle 4 is rotated in the proper direction to force down the sleeve 5, and as the latter descends the lug 26 acts on the valve 2 to close it, swinging said valve on its pivot 28 downward and forward until 90 the packing 29 is pressed hard against the valve-seat 8. Directly, too, the foot-piece 27 of the descending sleeve 5 encounters the projection 35 and forces the valve 3 with 95 its packing 32 down and clear of the valve-seat 11, thus opening a passage from the chamber 6 through said valve-seat, the outlet 10, the cap 12, and the opening 13 in the bottom of said cap. No more water can now 100 flow through the casing 1, and the pipes back of said casing are drained through the valve-seat 11, the waste water entering the chamber 6 from the normal outlet 9 and escaping by way of said valve-seat and the open parts below.

105 The sleeve 5 is guided by the ribs 25 and the grooved parts of the casing 1 in which such ribs travel, and these interengaging members insure the tight closing of the valve 2 for as long a time as said sleeve is permitted to remain in its low position.

110 When it is desired to turn on the water, simply rotate the spindle 4 in the opposite direction and thus elevate the sleeve 5, with the result that the foot-piece 27 is carried 115 away from the projection 35 and the valve 3 is released to the spring 34 and reseated or closed thereby, and the lug 26 is raised above the valve 2, leaving the latter free to be opened by the inrush of water.

120 Normally the valve 2 is left open so that it hangs loosely from the pivot or bolt 28 in the chamber 6, the valve 3 then being closed, as hereinbefore explained. In the event, therefore, that from any cause the water 125 back of the combination valve becomes hot enough to produce a pressure in excess of that from the street main, such excess pressure acts first on the valve 2 to close the same and thus shut off the supply, and then 130

such excess pressure overcomes the resistance offered by the spring 34 and opens the valve 3, so that it can escape through the waste way. The way to the water meter is thus closed against back pressure, and relief afforded to the pipes back of the combination valve, so that all liability of damage to such pipes is removed. As long as the back pressure continues to be excessive the valve 2 10 remains closed and the valve 3 open, but when said pressure is sufficiently reduced said valve 3 closes and said valve 2 opens, normal conditions of the device then being restored and maintained unless disturbed 15 or changed again by another accumulation or generation of back pressure, or until the sleeve 5 be operated to shut off the supply and open the waste. The relief action is entirely automatic as will be readily understood.

The guide ribs 25 and the lug 26, with the foot-piece 27 at their bases, depend from the annular portion or body of the sleeve 5, and all of such parts including said annular portion may be connected by webs 37-37 for the purpose of stiffening and strengthening the depending members.

This combination valve is so constructed that it can be repaired, should occasion require, without difficulty.

What I claim as my invention, and desire to secure by Letters Patent, is—

1. A combination valve, of the class described, comprising a casing having a supply inlet and supply and waste outlets, a loose valve subject to back-pressure control and free when open to be actuated by back pressure to close said inlet, and a normally-

closed valve subject to back-pressure control for opening said waste outlet. 40

2. A combination valve, of the class described, comprising a casing having a supply inlet and supply and waste outlets, a loose valve subject to back-pressure control and free when open to be actuated by back pressure to close said inlet, a normally-closed valve subject to back-pressure control for opening said waste outlet, and mechanical means for closing said loose valve and opening said normally-closed valve. 45 50

3. The combination, in a combination valve of the class described, with a casing having a supply inlet and supply and waste outlets, and provided with guide means, a flapper valve mounted in said casing for said inlet, a perforated cap attached to said casing at said waste outlet; a valve in said casing for said waste outlet, said valve having a stem projection, and a spring arranged in said cap to retain said valve normally in 60 closed position, of a reciprocable sleeve provided with depending guide means to engage said first-mentioned guide means, and further provided with a depending lug to engage and close said flapper valve, but leaving the latter free to be closed by back pressure, and with a depending foot-piece to engage said stem projection and open said waste valve, and a spindle arranged in said casing to reciprocate said sleeve, said foot-piece extending beneath said spindle. 65 70
